UNITED STATES PATENT OFFICE.

HARRISON B. WALTER, OF CHICAGO, ILLINOIS, ASSIGNOR, BY MESNE ASSIGNMENTS, TO CONTAINER CORPORATION OF AMERICA, OF CHICAGO, ILLINOIS, A CORPORATION OF DELAWARE.

BOX.

Application filed November 23, 1925. Serial No. 70,769.

This invention relates to improvements in boxes made of fibre or paper board or the like and consists of the matters hereinafter described and more particularly pointed out 5 in the appended claims.

The object of the invention is to provide a box of the kind which is adapted for use more particularly in the shipment of fruit, such for example as oranges, lemons, and 10 other citrus fruit, and which may be sent knocked-down or flat to the packer, who may quickly and easily set up the box ready for packing.

Another object of the invention is to provide 15 a box of the kind which is cheap and economical to manufacture and which at the same time is of great rigidity and strength, so that it will withstand the shocks and jars both from inside and from outside resulting 20 from the rough handling to which it is subjected in shipment.

Another object of the invention is to provide 25 a box of the kind, which, though made of fibre board, may be easily packed in a car and held in suitable spaced relation for the circulation of air in and about it when placed 30 in a row of boxes of the kind, by means of wood strips nailed to the boxes in the same way as in the case of the familiar wood fruit boxes.

The many advantages of my invention will appear more clearly as I proceed with my specification.

In the drawings:—

Figure 1 is a perspective plan view of the blank and parts connected thereto for forming the body of the box.

Figure 2 is a perspective view of the lid of the box.

Figure 3 is a perspective view of the part which forms the intermediate, transverse wall of the box.

Figure 4 is a perspective view of the box-body as it appears when set up and ready for packing.

Figure 5 is a perspective view of an end 50 of the box showing the marginal flaps at the top of the body in folded relation as when packed and ready for the application of the lid of the box.

Figure 6 is a perspective view of the box as it appears when loaded with the lid applied.

Figure 7 is a view showing the manner of

placing the boxes side by side with strips at 55 the front and rear ends nailed to the box ends for holding them in spaced relation.

Figure 8 is a perspective view showing a slightly modified form of the box.

Referring now to that embodiment of the 60 invention illustrated in the drawings:—10 indicates the blank for forming the sides and bottom of the box. This blank is an elongated sheet of fibre or paper board of a width equal to the length of the box to be 65 formed and of a length to provide two side walls 11, 11, an intermediately placed bottom wall 12, and lateral flap extensions 13, 13, of the side walls 11, 11, at the ends of the blank. The several parts of the blank referred to are defined and their lateral limits determined by four transverse creases 14. 70

15, 15 indicate narrow wood strips applied transversely to the marginal ends of the sides 75 11, 11 on their inner faces (their top faces as the parts appear in Figure 1). 16, 16 indicate similar, but preferably wider, transverse strips of wood, applied to the outer face (the bottom face as shown in Figure 1) of the bottom wall 12 at its marginal ends. 80 Said strips 15 and 16 are equal in length respectively to the width of the side walls 11, 11, and of the bottom wall 12, and are each preferably placed with an edge flush with the edge of the blank. They are secured to 85 the blank by means of staples or by any other suitable means.

17, 17 indicate blanks attached to the main blank and designed to form the end walls of the box. Said blanks may be provided 90 with holes or apertures as shown for purposes of ventilation. Each of these blanks is of the area of the end of the intended box,—that is to say, it is a width equal to the width of the bottom wall 12 of the blank 95 and its height is equal to the width of the side walls 11, 11 of the main blank. Each end blank as shown is provided with oppositely folding, top and bottom extensions 18, 19, defined by creases 18^a, 19^a. The bottom extensions 18 are of substantially the same width as the wood strips 15, 15 of the side walls 11, 11, and are secured by means of staples or other means to the marginal ends of the bottom wall 12 and to its wood strips 16. 100

The parts thus far described comprise the body of the box and when made and secured

together, as hereinbefore set forth, will lie flat, with one end blank 17 overlapped upon the other end blank, as shown in Figure 1, so that said body of the box may be shipped flat.

The novel box has an intermediate, transverse wall which in the preferred construction is duplex and consists of two blanks 20, 21, each having a main part of the width and depth of the box and each provided with a folding flap extension 20^a, 21^a, respectively. The two blanks are secured together with their main body parts in contact throughout and with their flap extensions 20^a, 21^a disposed to fold in opposite directions. Two staples 22, 22, preferably placed near the top edges of the blanks, secure them together, so as to provide a very rigid, intermediate dividing wall for the box.

20 The top or lid of the box is formed by means of a blank 23 of the length and width of the box, with three transverse wood strips 24, 24, and 25, like the wood strips 15 and 16 heretofore described, attached respectively at the marginal ends and at the middle of the blank 23.

The lid 23 and the intermediate, transverse wall 20 may be conveniently laid on top of the main body blank 10 and the said three parts thus assembled, constituting all the parts of the box ready to be set up, may be sent to the shipper flat or knocked-down.

To set up the box, the side members 11, 11 are folded on their crease lines 14, to bring them to vertical relation with respect to the bottom wall 12. In this movement, an end of each wood strip 15, 15 is brought to bear on top of the bottom flap extension 18 of the adjacent end blank 17. The end blanks 17 are then in succession folded into vertical position, with their lateral margins against the adjacent wood strips 15, 15 (see Figure 4) to which they are then secured by means of staples or other suitable attaching devices. The intermediate wall 20 is then inserted into the box-body with the respective folding extensions 20^a, 21^a, preferably disposed in opposite directions against the inner faces of the side walls 11, 11, to which they are attached by means of staples 26, 26. This completes the setting-up operation. The box, when set up, appears, as shown in Figure 4, with the several folding extensions of the sides 11, 11 and ends 17, 17, namely the folding extensions 13, 13 and 19, 19, disposed vertically so that the fruit or other goods to be packed in the box may be easily inserted thereinto.

After the box is packed, the several folding extensions or flaps 13, and 19, are folded down against the contents of the box,—the flaps 19, 19 of the end walls first, and then the flaps 13, 13 of the side walls down upon the flaps 19, 19, as shown in Figure 5. The lid is then placed on top of the box in posi-

tion to close it, in which position it is readily secured by means of nails or other convenient securing devices, which take through the wood strips 24 and the fibre blank of the lid, and through the flaps 19 and then engage 70 in the top ends of the strips 15 of the sides of the box.

When the box is thus packed, closed and sealed, as described, it will manifestly present a very strong and rigid structure. The 75 flaps 13, 13 at the top edges of the side walls and the flaps 19, 19 at the tops of the end walls of the box not only provide an inner marginal closure for the box so that when the lid is applied, the box is adequately 80 closed without gaps along the sides, but they also act as flanges to stiffen the sides and ends of the box at the top so as to reinforce it against jars or strains tending to bend or distort the walls of the box. In addition, 85 the box is still further reinforced by the wood strips at its ends which, together, with the fibre body, when the box is closed, provide a rigid combination fibre and wood rectangular frame at each end of the box. 90

It is customary in stacking wood fruit boxes to space them in rows in the car and to hold them so they will maintain the spaced relation by means of wood strips extending along the ends of the boxes and nailed thereto. Boxes made in accordance with the invention may be similarly maintained in rows with air-spaces 30 between adjacent boxes (see Figure 7) and wood strips 31 may be 100 nailed to the ends of the boxes with the nails taking through the strip 31 and engaging through the lid strips 24 and into the upright strips 15, 15 which constitute the side corner posts of the boxes.

If desired the box may be bound by a 105 wire or band in the transverse plane of the intermediate wall 20 and of the intermediate transverse wood strip 25 of the lid, said intermediate wall presenting the internal resistance required to withstand the binding 110 force of the wire or band.

A very good box of the kind may be made in which the lid 23 is omitted. Such a box is shown in Figure 8. In this case the closure flaps hinged to the side walls of the box 115 body are made wider so as to be capable together of providing a complete, instead of only a marginal closure for the box. In said figure, like parts are indicated by the same numerals heretofore used, with the superfix *.

13*, 13* indicate the closure flaps hinged to the side walls 11*, 11* of the box. Said flaps are wide enough to abut, or preferably to overlap as shown at the middle of the 125 box, thus completely closing it. The closure flaps 13* may be sealed in closed position by means of wood strips 24*, one at each end of the box, said wood strips being placed at the marginal ends of the closure flaps 13*.

transversely across them and then being secured in place by nails which take through said wood strips, through the marginal ends of the closure flaps and into the ends of the 5 side wood strips 15^x.

The many advantages of my invention will be manifest to those familiar with the art.

While in describing my invention I have 10 referred to many details of mechanical construction and arrangement of parts, it will be understood that the invention is not to be limited thereto, except as pointed out in the appended claims.

15 I claim as my invention:—

1. A box made of fibre board or the like comprising, a body blank cut and creased to provide a bottom wall, two side walls, and transverse wood strips secured to the inside 20 and outside faces respectively of said side walls and bottom wall at their marginal ends; end blanks each provided with a folding bottom extension secured to a marginal end of said bottom wall; and a lid consisting 25 of a blank and of transverse wood strips secured to the marginal ends of said blank.

2. A box made of fibre board or the like comprising, a body blank cut and creased to provide a bottom wall, two side walls and 30 lateral flap extensions of the side walls, and transverse wood strips secured to the inside and outside faces respectively of said side walls and bottom wall at their marginal ends; end blanks each provided with oppositely folding top and bottom extensions, 35 said bottom extensions being secured to the marginal ends of said bottom wall; and a lid consisting of a blank and of transverse wood strips secured to the marginal ends of 40 said blank.

3. A box made of fibre board or the like comprising, a body open on top and a lid

for closing said open top, the body having side, end, and bottom walls, and transverse wood strips attached to said bottom, side 45 walls and lid at their marginal ends in alternate arrangement, with some of the strips on the inside faces of said walls and the adjacent strips on the outside faces of said walls, said wood strips when the box is 50 closed, presenting a rigid combination wood and fibre rectangular frame at each end of the box.

4. A box made of fibre board or the like comprising, a body open at the top and a lid 55 for closing said open top, the body having side, end, and bottom walls and an intermediate transverse wall, and transverse wood strips attached to said bottom, side 60 walls and lid at their marginal ends in alternate arrangement, with some of the strips on the inside faces of said walls and the adjacent strips on the outside faces of said walls, said wood strips when the box is 65 closed, presenting a rigid combination wood and fibre rectangular frame at the ends of the box, and a transverse wood strip attached to said lid in the plane of said intermediate transverse wall.

5. A box made of fibre board or the like 70 comprising, a body blank cut and creased to provide a bottom wall, two side walls and lateral flap extensions of the side walls, and transverse wood strips secured to the inside 75 and outside faces respectively of said side walls and bottom wall at their marginal ends; and end blanks each provided with oppositely folding top and bottom extensions, and bottom extensions being secured 80 to the marginal ends of said bottom wall.

In testimony that I claim the foregoing as my invention, I affix my signature this 19th day of November, A. D. 1925.

HARRISON B. WALTER.
